UNITED STATES PATENT OFFICE.

PHILIP A. REUTTER, OF WATERBURY, CONNECTICUT, ASSIGNOR TO SCOVILL MANUFACTURING COMPANY, OF WATERBURY, CONNECTICUT, A CORPORATION OF CONNECTICUT.

REFILL HOLDER FOR VANITY BOXES.

Application filed March 27, 1924. Serial No. 702,199.

This invention relates to certain improvements in refill holders or clips for holding powder compacts in the small boxes or cases now commonly called vanity cases and to a case or box combined with such refill holder or clip.

These vanity boxes or cases are used for carrying cosmetic preparations, and certain types of the boxes are largely used for carrying a cosmetic in compact form, the cosmetic, either powder or rouge, being formed into a solid mass supported on some sort of a base, as a sheet of light metal, cardboard, glass, or the like. These powder compacts are brittle and easily damaged. They must, however, be securely held in the boxes so that powder may be removed from the compacts by rubbing with a puff or the like. Further, in the most popular types of boxes, these compacts are carried in the box so that they can be removed therefrom after the cosmetic is exhausted and a fresh compact placed in the box.

These compacts are held in the boxes by devices generally known as refill holders or clips, the compact being sprung into position in a clip and the clips removably inserted in the box. In thus filling the clips with the compacts the compact is liable to be chipped, and, furthermore, in the type of boxes where the cover and compact-holding compartment are secured together by a spring catch the operation of the catch is likewise liable to chip and thus mar the surface of the compact.

It is one object of the present invention to provide a refill holder or clip which shall have means for removably securing the clip in the box and means for holding the compact in the clip, these latter means being of such character as to embrace the edge of the compact support without substantial contact with the powder, the clip being also so designed as to hold the edge of the compact away from the wall of the box, thus giving room for the spring catch to operate where the compact is used in boxes employing spring catches. A further object of the invention is to provide a refill holder or clip which shall be simple and cheap, and which may be readily inserted in and removed from the box with which it is to be used.

With these and other objects not specifically referred to, the invention consists of cer-

tain novel parts, arrangements, and combinations, which will be fully described in the accompanying drawings and the novel features thereof pointed out in the claims hereunto annexed. 55

Referring now to these drawings, 60 Figure 1 is a central vertical section of a box embodying the invention;

Figure 2 is a horizontal section of the construction shown in Figure 1, the section being taken on line 2—2 of that figure; 65

Figure 3 is a vertical sectional view, the section being taken on the irregular line 3—3 of Figure 2;

Figure 4 is a detailed elevational view of the improved clip or holder, and 70

Figure 5 is a detailed sectional view, partly broken away, on an enlarged scale, showing the position assumed by the parts when a compact is loaded into the clip.

Referring now to these drawings, which 75 show the invention in its preferred embodiment, the box or case chosen to illustrate the invention is one in which the parts are secured together by a spring catch, the invention having been especially designed for use 80 in such a box, though as to some of its features it is useful in boxes of other types.

The particular box chosen to illustrate the invention is made of a light sheet metal of a size such that it may be conveniently carried in a handbag or in the pocket of the user. This box includes a bottom member 1 having an upstanding peripheral wall or flange 2, this flange near its upper end being inset as indicated at 3 to form an outer 85 rib or abutment 4, and an inner shoulder 5. This bottom member forms, in the box illustrated, a cosmetic compartment and it is closed by a cover 6, pivotally associated with the bottom by a hinge 7. This cover has a downwardly extended peripheral flange 8, which when the box is closed has telescopic engagement with the inset flange 3 of the bottom, the lower edge of the flange 8 resting 90 on the rib 4, as shown in Figure 3. A mirror 9 may, if desired, be secured in the cover of the box, this mirror being held in place by a ring 10 frictionally engaging the walls 95 of the cover.

The cover and bottom members are, in 100 boxes embodying the best form of invention, held together by a spring catch, which includes a spring arm 11 secured at one end

by a rivet 12 to the inner wall of the bottom of the box, this arm 11 at its free end having a projection 13 which engages a recess 14 formed in the cover of the box, the arm also being provided with a release 15 by which the spring arm is movable inwardly to release the catch when it is desired to open the box.

The bottom of the box is intended for the reception of a cosmetic, either powder or rouge, in the form of a compact. These compacts comprise a mass of powder 16, moulded on a plate 17, which is usually of light sheet metal, glass, or the like. These compacts are brittle and easily marred or chipped around the edges. In accordance with the invention, an improved holder or clip is provided for holding the compact so as to prevent marring or chipping when the compact is being loaded into the holder or when it is positioned in the box. The particular form of this compact holder may be, of course, somewhat varied, but it will include holding prongs for holding the compact in such a way that the engagement between the prongs and the compact occurs or takes place at the edge of the compact base, the prongs being substantially clear of the powder, and the holder will also include additional prongs by which the holder may be removably held in position in the box, the prongs being dimensioned so that the compact is held clear of the inside wall of the box.

In the particular construction illustrated, the holder will include a base or support which is, as shown, in the form of an annulus 18, this annulus, where the bottom of the box is flat, being likewise flat so as to fit snugly against the bottom of the box. This annulus is formed with a set of compact holding prongs and a set of prongs for removably securing the annulus in the boxes. These prongs are of spring metal and preferably are integral with the annulus itself. While the latter prongs or the prongs which hold the clip in the box, may be varied as desired in number, they are, to effect easy removal from the box, two in number, arranged diametrically opposed to each other, as shown in Figure 2, and each includes a long prong 19 which is bent upwardly, as indicated at 20, and then outwardly, as indicated at 21, to form an edge of substantial width which will engage beneath the shoulder 5, before referred to. The top edge 21 of one of the long prongs may be provided with an indented portion 22 forming the opening in which a pin or similar tool may be inserted to spring the edge out from under the shoulder when it is desired to remove the clip.

Arranged, preferably on each side of the long shoulder engaging prong 19, are compact holding prongs 23 and 24. These prongs are, as shown, inset relatively to the

long prongs so that the compact is held away from the long prongs and from the inner wall of the box, these compact holding prongs being struck on a shorter diameter than the long prongs. These compact holding prongs 23, 24 are formed with an upturned prong or leg 25, this leg, as shown, being formed so as to be slightly angular relatively to the annulus itself, as indicated at 26 in Figure 4. The outer edge of the prong is or may be slightly outturned, as indicated at 27, so as to clear the powder compact. The leg 25 is, as shown, shaped to engage the base 17 of the compact, this base being snapped into the prongs, as shown in Figure 5, and, as shown, when the compact is in place the prongs have bearing engagement with the compact only for about the height or thickness of the compact carrying base so that the prongs are kept substantially clear of the powder.

With this construction the compact is readily sprung into position in the clip and the clip placed in the box and there are no parts contacting with the surface of the powder which will tend to mar the same and the compact is held out of the way of the moving part of the springs where the compact is used in a box employing a spring catch. While the invention as shown and described is in what is believed to be its best form, it is to be understood that changes and variations may be made in the various forms of the clip or holder without departing from the invention, and that the clip or holder may be used in boxes other than those having a spring catch.

What I claim is:

1. A refill clip or holder comprising a base and spaced sets of prongs extending upwardly from the base, each set including a long prong having an outwardly turned edge for engagement with the wall of a box, and prongs on each side of the long prong and arranged inside the long prong at an acute angle to the base for engaging the edge of a compact plate or support between which the compact and its plate may be inserted vertically. 105

2. A refill clip or holder comprising a base and diametrically disposed sets of prongs extending upwardly from the base, each set including a holding prong for engagement with the wall of a box, and prongs inset therefrom at an acute angle to the base on each side of the holding prong for engaging the edge of a compact plate or support between which the compact and its plate may be inserted vertically. 110

3. A refill clip or holder comprising a base, spaced prongs extending upwardly from the base having an edge outwardly turned for engaging the wall of a box, and prongs arranged in groups for engaging a powder compact support below the powder, 115

all the latter prongs being inset from the box engaging prongs at an acute angle to the base to hold the compact plate away from the wall of the box.

- 5 4. A refill clip or holder comprising a flat ring having spaced box engaging prongs extending outwardly and then upwardly from the edge of the annulus, and shorter prongs extending outwardly and upwardly from the edge of the annulus and on each side of and adjacent the box engaging prongs and inset therefrom.
- 10

5. A refill clip or holder comprising a base, and sets of prongs arranged at a plurality of points about the base, each set including a 15 long clip holding prong and two short prongs arranged on each side of the long prong closely adjacent thereto and inset therefrom between which the compact and its plate may be inserted vertically. 20

In testimony whereof, I have hereunto set my hand.

PHILIP A. REUTTER.
